UNITED STATES PATENT OFFICE.

WILLIAM H. VOSS, OF DAVENPORT, IOWA.

LINK DRIVING MECHANISM FOR WASHING MACHINES.

Application filed January 26, 1925. Serial No. 4,671.

This invention relates to operating mechanism for washing machine tubs and similar apparatus.

In general, the invention relates to certain improvements in the details of construction of the apparatus disclosed in my pending application, Serial No. 631,493, filed April 12, 1923.

Among the objects of my invention are to provide an improved construction of the oscillatable link member by which the source of power from the motor or other prime mover is transmitted to the washing machine tub or other power driven member.

A further object of my invention is to provide a more simple and compact link construction which will not only permit the facile assembly of the link but also the power transmitting levers which connect thereto and to the control rod for adjusting the throw of the tub. A further object is to provide an improved constructional arrangement for enclosing the sides of the tub and for permitting the control handle for the link adjusting mechanism to project outwardly through the side of the tub to an accessible control position; to provide these and other features which will be more readily apparent from a perusal of the following specification when taken in connection with the accompanying drawings wherein:—

Figure 1 is a side view partly in section and partly broken away showing the interior driving mechanism for the tub.

Figure 2 is a plan view taken on a section line through Figure 1 immediately below the tub.

Figure 3 is a sectional view through the oscillating links and the control member.

Figure 4 is a side view of the oscillating link and the connections to the tub and control members.

Figure 5 is a somewhat similar view showing the control member shifted to the upper portion of the oscillating links, and,

Figure 6 is a perspective view of the un-assembled link member.

Referring now to the drawings in detail, the washing machine comprises the usual frame work consisting of the four upright posts preferably arranged in the form of a square box-like frame. These corner posts, which are preferably of L-shaped formation, are suitably braced by cross supports 5, 6, 7,

8 and 9 whereby to provide a rigid structure on which the operating mechanism may

be rigidly mounted. In addition a diagonal support 10 is provided so that a short support 11 hereinafter referred to may be rigidly attached thereto at the point 12. As shown in Figure 1, the support for the driving mechanism is borne by the side posts at a sufficient elevation to permit the motor M and large driving wheel to depend therefrom. The two top frame supports 13 of the tub and its corresponding opposed member constitute the mounting for the tub which in the present instance is of the oscillatable type. Obviously, the link control mechanism described hereinafter is applicable to other types of agitator machines. As shown in Figure 1, the upper bar 13 is provided with the journal 14 in which is mounted the shaft 15 rigidly carrying the tub.

The motor M is carried by the cross-members 6 and 8 from a cross-shaft 16 in such a manner as to depend therefrom, as shown in my prior application hereinbefore set forth. The motor is provided with a pulley 17, driving a belt 18 running over a large driving wheel 19. This wheel is fixed to a shaft 20 having its bearings on the cross-bars 6 and 9 respectively. The shaft 20 is provided with a small pinion 21 meshing with a large wheel 22 on a shaft 22' journaled on the cross-bar 9 and in a bearing 22'' formed in one of the side wall members.

The wheel 22 is provided with a crank 23 to which is pivoted a rod 24. Inasmuch as the constructional arrangement of the motor and gearing and its mountings is disclosed in my before mentioned pending application, no further allusion will be made thereto.

The link driving mechanism which forms one of the features of this present invention is oscillatably mounted on the frame supports and is adapted to be driven by the reciprocable connecting rod 24 and in turn forms a driving connection with the rockable tub and forms an element of a power controlling, power transmitting member interposed between the prime mover and the oscillatable tub. In the present invention the cross bars 8 and 11 are provided with suitable bearings 25 and 26 to receive the oppositely extending axles or pivotal members of the link. The assembled link is shown in Figure 6 of the drawings.

My improved oscillatable link is preferably composed of two frames or castings 30

and 31, each of which is formed with a flange 32 and a laterally extending plate 33 so that when the frames are bolted together by means of bolts 34 the plates 33 will be rigidly maintained in spaced position. Each of the plate portions of the frame is provided at its bottom and at its exterior face with an outwardly extending lug 35 bearing an axle or shaft 36 which forms the axis of oscillation of the link. In addition each plate is provided with a longitudinally extending slot 37 which extends from a point coincident with the axles of oscillation 36 of the link upwardly substantially to the top of the plate. These slots 37 are in register. In addition one of the plates is provided with an ear 38' which forms a pivotal connection with the driving rod 24. By means of this connection when the rod 24 is reciprocated by means of the gears 22 the link will be oscillated about its oppositely extending axles 36 which as before stated are journaled, in the spaced bearings 25 and 26. A pin 38 extends across the space between the two plates 30 and 31 with its ends lying in the registering slots 37. A lever 39 is pivoted around the central portion of this pin and is connected at its other end at 40 to the base of the tub. Means is provided for shifting pin 38 along the slot 37 and longitudinally of the link thereby to guide the travel of the pin 38 as the link is oscillated and thereby vary the throw of the tub from an extreme position at which the pin 38 is at the upper end of the slot as shown in Figure 5 to another extreme position wherein the pin 38 is at the bottom of the slot and coincident with the axis of oscillation 36 of the link all shown in Figure 4. This means comprises a rod 41 pivotally disposed on pin 38 between the furcations of lever 39 as shown in Figure 3. The bottom portion of rod 41 is pivoted as at 41' to a rod 43 which is bent at right angles to itself as at 44 and is journaled in blocks 45 carried on the cross-bars 6 and 8. The other end of this rod 44 terminates in a collar 46 formed with an integral upwardly extending finger 47 having integral therewith a half collar 48 which in conjunction with a similarly formed half-collar 49 forms a detachable connection to the bottom of a control rod 50. Thus by shifting this control rod 50 the rod 44 will be turned in its bearing 45 and through the pivotal connection 46 and the pivotal connection with the pin 38 shifts the pin 38 lengthwise of the slot 37. It is to be noted that when the pin 38 is in the lowermost position as shown in Figure 4, the link is free to oscillate without in any way reciprocating the rods 43 and 44 and it is likewise to be noted that when the pin 38 is in the upper portion of the slot, as shown in Figure 5, the pivotal pin 41' will be coincident with

the axis of oscillation 36 of the link so that again no motion is transmitted to the rod 44 when the link continues to oscillate. Hence no reaction will be placed on the control member when the link is being shifted and while the link is being oscillated.

In the present invention the sides of the frame between the four upright corner posts, are covered so as to protect the operator from any possible injury from the driving mechanism. In this preferred form two of the sides are permanently closed by sheet metal coverings 58 and 59 while the two remaining sides are covered by doors 50 and 51 which are preferably pivoted to the frame member so as to be hinged thereon. These hinges are shown at 52. Any desirable type of latch for maintaining these doors in locked position may be used. In the present invention each of the doors is provided with a latch 53 which is adapted to be turned so that a tongue 54 engages behind one of the frame members or cross supports. By opening these doors 50 and 51 access may be had to the entire driving mechanism of the washing machine.

For the purpose of permitting the control rod 50 to project upwardly to a point near the upper face of the tub, the side 59 of the tub is provided with an arcuate slot 54 through which the rod 50 projects. The upper end of this rod 50 is provided with a handle 55 and the upper shank of the rod 50 is adapted to engage retaining grooves disposed in blocks 56 and 57 on the cross-supports 13. If desired, any number of these grooves may be arranged so that the control rod 50 can be held in any intermediate position.

In operating the mechanism herein described, the motor drives a large pulley 19 by means of the belt 18 and pulley 19 in turn drives the lower gear 22 through the small pinion 21. A crank arm on the gear 22 in turn reciprocates rod 24 which by means of its pivotal connection with the link constantly oscillates the link about its axis of oscillation 36.

With the driving mechanism in the position shown in Figures 1 and 4 of the drawings, it must be evident that no power is transmitted to the washing machine tub because the pin 38 is coincident with the axis of oscillation of the constantly oscillating link and since pin 38 is not moved arcuately, the connecting lever 39 will not be moved. For the same reason control rods 41 and 43 will not be moved. Hence no motion will be communicated back to the control rod 50. If it be desired to start the washing machine tub in oscillation, the control rod is moved from the position shown in Figure 1 to the right in which event the pin 38 is moved upwardly in the slot 37 by means of the control rods 43 and 41 and the lever 39 is im-

mediately given a throw corresponding to the height of adjustment of pin 38 in the slot 37. As the pin 38 is moved upwardly along the slot the throw of the tub is gradually increased until the pin reaches the end of the slot as shown in Figure 5 which corresponds to the high speed or maximum rocking of the tub. In this position the pivotal pin 41' connecting the control rod 41 to the control rod 43 is coincident with the axis of oscillation of the link so that no motion is communicated to the control rod 43. From an inspection of Figure 3 of the drawings, it will be noted that by reason of the spaced journals 25 and 26 and the improved construction of links wherein it is composed of two halves bolted together as at 34 and each half provided with an outwardly extending pivot 36 adapted to be carried by these bearings 25 and 26, all reactive thrust is adequately taken care of and a very durable and steady structure provided. In addition, this arrangement provides great simplicity in the manufacturing and in assembling operation. Likewise the arrangement of the interfitting forked control rod enveloping the inner pivotal end of the lever 39 and bearing on the pivotal pin 38 disposed in the slot 37 also provides a compact construction.

It must be manifest that other constructional details are within the contemplation of the broad spirit of this invention.

Having thus described my invention, I claim:

1. In a device of the class described, the combination of a support, a tub shiftably mounted thereon, a link having a bearing forming an axis of oscillation, said link being formed of two plates spaced apart and provided with registering slots extending longitudinally thereof from said axis of oscillation, a pin extending across said plates therebetween with its ends lying in said slots, a rod having a fork pivoted to said pin and to the tub, a control rod pivoted to said pin between the furcations of said fork and means for oscillating said link.

2. In a washing machine, the combination of a support, a tub rockably mounted thereon, a link having a bearing forming an axis of oscillation, said link being formed of two plates, portions of said plates being spaced apart, corresponding longitudinal edges of said plates being secured together, correspondingly located longitudinal slots in said plates, a pin extending across said plates therebetween with its ends lying in said slots, a rod having a fork pivoted to said pin and to the tub, a control rod pivoted to said pin between the furcations of said fork and means for oscillating said link.

In witness whereof, I hereunto subscribe my name to this specification.

WILLIAM H. VOSS.
